UNITED STATES PATENT OFFICE.

ACHILLE LÉON FRANCOIS WATTÉL, OF SEVRES, FRANCE.

AUTOMOBILE-LOCKING APPARATUS.

1,395,881.

Specification of Letters Patent. Patented Nov. 1, 1921.

Application filed July 31, 1920. Serial No. 400,557.

To all whom it may concern:

Be it known that I, ACHILLE LÉON FRANCOIS WATTÉL, a citizen of the French Republic, residing at 22 Avenue de Bellevue, 5 Sevres, in the Department of Seine et Oise, France, have invented a new and useful Automobile-Locking Apparatus, of which the following is a specification.

The present invention relates to an apparatus designed to cut off the ignition for the engine, to cut off the electric current from the battery of accumulators to the starting-motor and to immobilize the car by locking the shaft driving the differential, by 10 the manipulation of a handle, and in this way to render the theft of the car impossible even if towed and to render it impossible to use the car without the consent of the owner.

20 In a general way, the invention comprises a shaft operated by a handle which can be locked in three positions; along its length this shaft carries two electric switches and at one end a cam-plate acting upon a spring- 25 pressed bolt which can immobilize the transmission shaft, the handle being inclosed in a box, which can be locked, while each of its three positions corresponds to normal running, interruption of the electric circuit 30 for ignition and starting, and finally, in addition, immobilization of the transmission shaft of the car.

The invention is illustrated by way of an indicative example in the accompanying 35 diagrammatic drawings, in which;

Figure 1 is an elevation, partly in section, of the general arrangement of the apparatus.

Fig. 2 is a plan view of the segment for 40 immobilizing the handle.

Fig. 3 is a detail view of the spring-pressed bolt for the transmission shaft, and

Figs. 4 and 5 are detail views of the mounting of the handle upon its shaft.

45 1 represents the actuating handle pivoted at 2 upon the shaft 8 in such a manner that, when it is raised, its pin 3 is disengaged from the notches 5, 6, 7 of the fixed segment 4, according to the position it is desired to 50 give to the handle 1, while it can then be immobilized in this position by causing the pin 3 to enter the corresponding notch.

The shaft 8, actuated by the handle 1, is supported by the bearings 4 and 9 and carries at its extremity the cam-plate 10. A lever 11 pivoted on the support 12 is held

in contact with the cam by the spring 13 supported at 14. A pinion 15 is keyed on the transmission shaft. The shaft 8 also carries a switch 16 connecting the battery of accumulators to the starting motor, as well as a switch 17 for cutting off the igniting current in case current from the battery is employed, or for connecting to the engine-body in the case of the use of a magneto. 60 The handle 1 is inclosed in a box 18 which can be locked and is placed upon the dashboard of the car or under the front seat. 65

The method of operation is the following: When running the pin 3 of the handle 1 occupies notch 5, as shown in the drawing.

If the driver wishes merely to cut off the current and to allow the car to be moved, either for towing purposes or for moving about a garage, he places the handle in position 6; the switches 16 and 17 have cut off the current, the engine can no longer operate and the lever 11 still retains the same position being held by the high portion of the cam, which latter has a flat surface 10'. If the pin 3 of the handle 1 is placed in the notch 7, the lever 11 leaves the high part of the cam 10 and locking of the pinion 15 takes place by the lever 11. In case the locking tooth of the lever 11 falls upon one of the teeth of the pinion 15 at the time of operating the handle, the slightest movement of the car, forward or backward, will cause rotation of the pinion and will permit of locking by the lever snapping into the recess either in front or in the rear of the tooth upon which the lever 11 was resting (Fig. 3).

When the lid of the box 18 is closed 95 and locked it is impossible to operate the handle through the intermediary of the shaft 8 as its position is fixed by the pin 3 in the notch which has been selected.

The device for locking the transmission 100 shaft is of course inclosed in a casing in order to prevent easy access to the tooth of the lever 11 for the pinion 15 for the purpose of disengaging it.

The invention has been described purely 105 by way of an example and it is obvious that numerous modifications could be made in details without departing from the spirit thereof.

I claim:

1. An apparatus for immobilizing an automobile, comprising a handle, a shaft adapt-

ed to be rotated by said handle, circuit-making and breaking means upon said shaft, means carried by said shaft for locking the transmission shaft of the car, a notched segment for holding said handle in the desired position and a box having a lock inclosing said handle.

2. An apparatus for immobilizing automobiles comprising a handle, a shaft adapted to be operated by said handle, circuit making and breaking means for the ignition and starting current on said shaft, a pinion on the transmission shaft of the car, a locking member adapted to engage said pinion,

a cam on said shaft for disengaging said locking member from said pinion, a spring adapted to force said locking member into engagement with the teeth of said pinion, a notched segment for holding said handle in the desired position, a box with a lock inclosing said handle and segment, and a closed casing surrounding said locking member and pinion.

ACHILLE LÉON FRANCOIS WATTEL.
